(57) **CLAIM**

The ornamental design for an electrical alarm and remote control, as shown and described.

DESCRIPTION

FIG. 1 is a front, side perspective view of an electrical alarm and remote control showing my new design, the electrical alarm and remote control shown in the “on” position;

FIG. 2 is a rear, side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, side perspective view of an alternate embodiment of the electrical alarm and remote control of FIG. 1, the electrical alarm and remote control shown in the “off” position;

FIG. 10 is a rear, side perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.
